(57) **CLAIM**

I claim the ornamental design for a grain sampler, as shown and described.

DESCRIPTION

FIG. 1 is a top plan view of the grain sampler.

FIG. 2 is a side elevation view of the grain sampler.

FIG. 3 is a bottom plan view of the grain sampler.

FIG. 4 is a front end view of the grain sampler.

FIG. 5 is a rear end view of the grain sampler.

FIG. 6 is a top perspective view of the grain sampler; and, FIG. 7 is a bottom perspective view of the grain sampler.
